UNITED STATES PATENT OFFICE.

THOMAS E. MURRAY, OF NEW YORK, N. Y.

DESIGN FOR AN ELECTRIC-FUSE CASE.

No. 39,735.

Specification for Design.

Patented Dec. 29, 1908.

Application filed September 28, 1908. Serial No. 455,222. Term of patent 7 years.

To all whom it may concern:

Be it known that I, THOMAS E. MURRAY, a citizen of the United States, residing at New York, county of New York, State of New York, have invented a new, original, and ornamental Design for Electric-Fuse Cases, of which the following is a specification, reference being had to the accompanying drawing, forming part thereof.

Figure 1 is a perspective view of an electric

fuse case showing my new design. Fig. 2 is a side elevation, Fig. 3 an end elevation and Fig. 4, a plan view.

I claim:

The ornamental design for an electric fuse case, as shown.

THOMAS E. MURRAY.
